UNITED STATES PATENT OFFICE.

DANIEL DIVER, OF CALGARY, ALBERTA, CANADA.

MACHINE FOR SEPARATING GOLD, SILVER, AND THE LIKE FROM SANDS.

1,254,484.

Specification of Letters Patent. Patented Jan. 22, 1918.

Application filed April 14, 1917. Serial No. 162,211.

To all whom it may concern:

Be it known that I, DANIEL DIVER, a subject of the King of Great Britain, and resident of the city of Calgary, in the Province of Alberta and the Dominion of Canada, have invented certain new and useful Improvements in Machines for Separating Gold, Silver, and the like from Sands, of which the following is a full description.

10 This invention relates to a machine for separating gold, silver, and the like from sands in which they are found, and the objects of the invention are to increase the efficiency of the machine, to render the several parts readily accessible for inspection during the process of separation, so that each step of the process may be readily observed, to simplify the several parts of the machine and adapt the same to better perform the 20 functions required of them.

With the above and other objects in view, the invention consists essentially of the improved construction particularly described and set forth in the following specification 25 and accompanying drawings forming part of the same.

In the drawings,

Figure 1 is a front elevation, partly sectional, of a machine embodying the present 30 invention.

Fig. 2 is a side elevation of the same.

Fig. 3 is an enlarged view of a detail.

Like characters of reference refer to like parts in the several figures.

35 Referring to the drawings, A represents a hopper or chamber having a serrated and angularly disposed bottom 10 and provided with a plurality of discharge conduits 11 at the lower end thereof, through which the 40 sands delivered to the said hopper are discharged.

These conduits are located above the inverted conical tubular members 12 superimposed on the upper end of the pipes 13, 45 which are provided with openings 14 in the walls thereof through which air or the like is designed to pass during the operation of the machine.

An injector nozzle 15 is inserted in each 50 pipe 13, intermediate of the height thereof, the nozzle being downwardly disposed and bell shaped, and connected through the pipe 16 with a suitable container 17 containing fluids such as steam, air or water under pressure, 55 sure, the delivery of the fluids to the nozzles being controlled by the valve means 18.

The lower or discharge end of the pipes 13 are located above cups 19 which are designed to contain mercury, the said cups and the lower end of the said pipes being housed 60 in a suitable casing 20, the lower end of which is formed with inwardly tapering walls 21 terminating in a discharge conduit 22.

This discharge conduit 22 is located above 65 a dished screen 23 which is operatively supported by the links 24 from the frame 25 surrounding the lower end of the casing 20, oscillating motion being applied to the screen 23 by a cam 26 which is operatively 70 connected thereto through the rod 27.

During the oscillation of the screen 23, an upward motion takes place simultaneously with the lateral motions.

The screen 23 is located in a bath 28 operatively supported from the frame 25 by the links 30 and is oscillated from the cam 31 by means of the rod 32. This cam 31 and the cam 26 are arranged at substantially right angles to each other so that when the 35 said cams are in operation, the screen 23 and bath 28 respectively will be oscillated in different directions transversely to each other, while at the same time they will also be actuated in a vertical direction. 85

The bottom of the chamber 28 is formed with a recess 33, adapted to hold or collect the mercury utilized in the amalgamation of the gold and silver contained in the sand being treated. 90

When this machine is in use, the sands from the hopper A are delivered through the conduits 11 to the conical members 12 and pass through the pipes 13, under the action of gravity. During this operation 95 there is an entraining action on the atmospheric air which passes in through the openings 14, and as the sands pass downward through the pipes 13, water, steam, air or other fluid, under pressure, is admitted into 100 the pipe through the inverted nozzle 15 supplied from the container 17.

This injecting fluid creates a downward pressure in the pipes 13, which imparts a relatively different velocity to the particles 105 of sand and metal values, causing a separation of them. Both the sand and mineral particles are then blown against the mercury contained in the cups 19, whereupon the gold and silver amalgamate with the 110 mercury and the sand, and any particles of the mercury and other minerals are blown

off the cup 19 and discharge through the conduit 22 into the screen 23.

- This screen is during this operation subjected to an oscillating and vertical motion 5 already described, which causes the sand in the screen to be moved in a direction transversely across the surface of the mercury contained in the bath 28, which is actuated by a cam 31.
- 10 The mercury is thus separated from the sands which are then drawn off, in any convenient manner, and the mercury is subsequently removed and treated in the usual manner to recover the metallic values 15 therein.

As many changes could be made in the above description and many apparently widely different embodiments of my invention within the scope of the claims constructed without departing from the spirit or scope thereof, it is intended that all matter contained in the accompanying specification and drawings shall be interpreted as 20 illustrative and not in a limited sense.

25 What I claim as my invention is:

1. An apparatus for the purpose specified comprising a bath, a container therefor, a screen operatively mounted in the bath, means for oscillating the screen as a unit, and means for oscillating the bath and container in a direction transversely to the screen.
2. An apparatus of the class described comprising a bath, a container therefor, a screen located in the bath, means for oscillating the screen as a unit and simultaneously actuating the same in a vertical direc-

tion, and means for oscillating the bath and container transversely to the screen simultaneously actuating the bath in a vertical 40 direction.

3. An apparatus of the class described, comprising a bath, a container therefor, a screen having dish sides in the bath, cam means for oscillating the screen as a unit 45 and eccentric means for oscillating the bath and container in a direction transversely to the screen.

4. An apparatus of the class described, comprising a screen, links operatively supporting the screen, a bath container, links operatively supporting the bath, said screen being submerged in the bath container, cam means for oscillating the screen and eccentric means for oscillating the bath container 50 at substantially right angles to the screen.

5. An apparatus of the class described, comprising a bath container having a depression in the bottom thereof, a screen operatively mounted in the bath, links pivotally supporting the screen, links pivotally supporting the bath container, eccentric means for oscillating the screen and simultaneously elevating the same and eccentric means for oscillating the bath container 55 transversely to the screen and simultaneously elevating the same.

In witness whereof I have hereunto set my hand in the presence of two witnesses.

DANIEL DIVER.
